CLAIM

The ornamental design for an single dual port network device, substantially as shown and described.

DESCRIPTION

FIG. 1 is a perspective view of a first embodiment of a single dual port network device, showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof; and

FIG. 7 is a front view thereof;

FIG. 8 is a perspective view of a second embodiment of a single dual port network device showing our new design;

FIG. 9 is a top view thereof;

FIG. 10 is a perspective view of a third embodiment of a single dual port network device, showing our new design; and,

FIG. 11 is a top view thereof.

The broken lines depict portions of the single dual port network device that form no part of the claimed design of the emobodiments, in which they are shown. The bottom, right
